UNITED STATES PATENT OFFICE.

EDWARD F. FITZGERALD, OF PHILADELPHIA, PENNSYLVANIA.

VALVE.

1,093,121.

Specification of Letters Patent. Patented Apr. 14, 1914.

Application filed February 6, 1913. Serial No. 746,633.

To all whom it may concern:

Be it known that I, EDWARD F. FITZGERALD, a citizen of the United States, residing at Philadelphia, in the county of Philadelphia and State of Pennsylvania, have invented new and useful Improvements in Valves, of which the following is a specification.

My invention relates to new and useful 10 improvements in valves, and is designed for use more especially in connection with the valve shown and described in my patent application, Serial Number 644,740 filed August 18th, 1911.

15 One of the objects of my invention is to provide a cap which is secured to the valve stem outside of the valve casing, said cap carrying means for limiting the movements of the valve plug thereby indicating when 20 the valve is shut off or opened.

Another object of the invention is to provide the cap with two stops, one of which is stationary and the other adjustable, the adjustable stop being used to indicate what 25 portion of the outlet of the valve plug is in communication with the outlet of the valve casing.

A further object of the invention is to construct the cap in such a manner that the adjustable stop will be protected and prevented from coming in contact with exterior 30 obstructions.

A still further object of the invention is to provide a filter for the steam which will 35 separate the water therefrom and prevent said water from passing into or through the valve. A valve made according to my improvement is especially adapted for use with radiators and prevents the water carried by 40 the steam from passing into the radiator and also permits the flow of steam into the radiator to be regulated, and after the desired flow has once been obtained, the same flow can be had each time the radiator is 45 used.

With these ends in view, this invention consists in the details of construction and combination of elements hereinafter set forth and then specifically designated by the 50 claims.

In order that those skilled in the art to which this invention appertains may understand how to make and use the same, I will describe its construction in detail, referring by numerals to the accompanying drawing 55 forming a part of this specification, in which—

Figure 1, is a side elevation of the valve casing. Fig. 2, a longitudinal sectional view thereof showing the valve plug and other 60 parts thereof. Fig. 3, an end view of the casing. Fig. 4, a face view of the cap. Fig. 5, a side elevation thereof. Fig. 6, a side elevation of the steam filter. Fig. 7, a plan view thereof, and Fig. 8, a perspective 65 view of a steam strainer.

In carrying out my invention as here embodied, 2 represents the casing having a passage way 3 therethrough which may be divided into an inlet opening 4, the valve 70 plug opening 5 and the stem opening 6, the stem opening 6 being reduced in size thereby forming a shoulder 7. The walls of the valve plug opening converge toward the stem opening thus forming a conical recess. 75 From the side of the casing leads an outlet arm 8, having an outlet opening 9, therethrough which communicates with the valve plug opening 5. This outlet arm and also the inlet portion of the casing are both 80 threaded as indicated by 10. The casing is preferably provided with a flange 11 at the stem end of the casing and this has formed therewith a lug 12 and if found desirable the flanges may be provided with indication 85 marks 13.

In the valve plug opening 5 is mounted the conical valve plug 14 having a longitudinal axial opening 15 leading from the larger or base end thereof to a suitable point intermediate its ends and from said opening 15 leads the outlet 16 which is adapted to register with the outlet 9 of the casing. The smaller end of the valve plug carries a stem 17 on which is mounted a suitable hand operating device such as a wheel 18. On said stem is also mounted a collar 19, the inner face of which engages the end of the casing. This collar has formed therewith, throughout a portion of its circumference, a depend- 100

ing flange 20 which overlies the flange 11 formed with the casing as well as the lug 12, said flange 20 preventing obstructions from coming in contact with the lug 12 as well as 5 the adjustable stop to be hereinafter described. With the flange 20 is produced an inwardly projecting extension 21 forming a groove 22. A set screw 24 passes entirely through the collar and engages a suitable 10 cavity 25 formed in the valve stem 17 thereby preventing the accidental displacement of the collar with relation to the stem.

27 represents a stop screw threaded through the flange 20 adjacent one end thereof, so that said screw projects into the groove 22 in which is mounted an adjustable stop 26 formed from a strip of spring metal. The 15 adjustable stop 26 is fitted within said groove by cutting the same to the desired 20 length, and the measurements for said stop are obtained by turning the stem 17 until the stop screw 27 contacts with the lug 12, after which the stem 17 is turned in the opposite direction, any desired distance and 25 stopped when the predetermined opening is reached, which is indicated by the indication marks 13. When the stem 17 is in the last named position the distance between the stop screw 28 and the lug 12 is measured and the 30 adjustable stop 26 is cut to fit therebetween.

When the valve plug 14 is turned so that the valve is shut off, the stop screw 27 will be in contact with one side of the lug 12 and stop the valve plug from further movement 35 in that direction. When the valve plug is opened the same is rotated until the end of the stop 26 contacts with the opposite side of the lug 12 and the valve plug will be stopped in its movement in this direction and the 40 predetermined opening maintained.

In the larger or base end of the valve plug is produced a filter cavity 30 provided with 45 threads 31 and in this cavity is mounted the filter 32. The filter comprises an annular body 33 provided with threads 34 and a flange 23, said body and flange having vertical 50 grooves or channels 35. The body carries a neck 36 which in turn carries an approximately hemispherical head 37 having grooves 55 or channels 38 therein which follow the curvature of the head and meet at the apex or pole thereof. When the filter is mounted in its position, the head will lie across the opening 15 in the valve plug and engage the 60 walls thereof so that the only passage ways from the supply pipe to the valve plug are through the channels 35 and 38. The body of the filter has a chamber 39 produced therein and when the steam is flowing to the valve it will come in contact with the filter and because of the arcuate surface of the chamber 39, the steam will be deflected and any water contained therein will run back into the supply pipe while the drier steam will pass around

the body of the filter through the channels 35 65 into the filter cavity 30 and then through the channels 38 into the opening 15. As the steam passes through the last named channels 38, any water that may have come through the first portion of the filter will be 70 retained at this point and then gradually flow back into the filter cavity 30 then through the channels 35 in the body of the filter to the supply pipe.

40 represents the steam strainer preferably 75 formed from a piece of tubing open at both ends and is slit longitudinally to produce openings 41. Said strainer is mounted in the opening 15 in the valve plug and lies 80 across the outlet 16.

In practice, the channels 35 in the body of the filter should be the largest openings, the channels 38 on the head of the filter, smaller, and the openings 41 in the strainer, smallest, so that if the water passes through one set 85 of openings it will not pass through the second or third set.

Of course I do not wish to be limited to the exact details of construction as here shown as these may be varied within the 90 limits of the appended claims without departing from the spirit of my invention.

Having thus fully described my invention, what I claim as new and useful, is—

1. In combination with a valve consisting 95 of a valve casing and a valve plug, said valve plug having a single passage way therethrough and provided with a filter opening in its base end, said filter opening being provided with threads, a filter comprising a body and a neck and an approximately hemispherical head, said body being provided with threads for mounting the filter in the filter opening, said body also having a chamber in the outer end acting as 100 a deflector, and vertical channels disposed around the outer circumference, the head being provided with channels in its arcuate face, said channels forming the only passage ways to the interior of the valve plug when 110 the filter is in position.

2. In combination with a valve consisting 115 of a valve casing and a valve plug, said valve plug having a single passage way therethrough and provided with a filter opening in its base end, said filter opening being provided with threads, a filter comprising a body having vertical channels, said body being mounted in the filter opening, a neck carried by the body and a head carried by 120 said neck, said head having channels therein, the channels in the body and head forming the only passage to the valve plug opening when the head is disposed across said opening.

3. In combination with a valve consisting 125 of a valve casing and a valve plug, said valve plug having a passage way therein

and having an outlet leading therefrom, and further provided at its base end with a filter opening, a strainer mounted in the passage way overlying the outlet therefrom, and a 5 steam filter mounted in the filter opening as specified.

In testimony whereof, I have hereunto

affixed my signature in the presence of two subscribing witnesses.

EDWARD F. FITZGERALD.
